US0D1073512S

(12) **United States Design Patent** (10) Patent No.: **US D1,073,512 S**
(45) Date of Patent: ** May 6, 2025

(54) **CASE FOR SECURITY AND AUTOMATION DEVICES**

(71) Applicant: **AJAX SYSTEMS CYPRUS HOLDINGS LTD**, Nicosia (CY)

(72) Inventors: **Oleksandr Konotopskyi**, Kyiv (UA);
Ilshat Garipov, Haapsalu (EE)

(**) Term: **15 Years**

(21) Appl. No.: **35/520,140**

(22) Filed: **Jan. 9, 2024**

(80) **Hague Agreement Data**

Int. Filing Date: **Jan. 9, 2024**

Int. Reg. No.: **DM/235260**

Int. Reg. Date: **Jan. 9, 2024**

Int. Reg. Pub. Date: **Mar. 1, 2024**

(51) **LOC (15) Cl.** **10-05**

(52) **U.S. Cl.**

USPC **D10/121**

(58) **Field of Classification Search**

USPC D10/106.1, 106.95, 121

See application file for complete search history.
